OXIDATION OF BARBITURIC ACID TO
ALLOXANWilhelm Wenner, Upper Montclair, N. J., assignor
to Hoffmann-La Roche, Inc., Roche Park, Nut-
ley, N. J., a corporation of New JerseyNo Drawing. Application November 20, 1944,
Serial No. 564,413

11 Claims. (Cl. 260—257)

My invention relates to a new method of making alloxan by direct oxidation of barbituric acid. The method is of interest because alloxan has in recent years become an important intermediate for the synthesis of riboflavin.

By direct oxidation I mean that barbituric acid itself and not as heretofore a derivative thereof is used as initial material which through the action of an oxidizing agent is converted into alloxan according to the formula

No method of direct oxidation of barbituric acid to alloxan has heretofore been recorded in literature.

Those cases in which barbituric acid itself was exposed to the action of an oxidizing agent did not result in alloxan and they do not suggest that direct oxidation is possible. Thus, nitric acid converts barbituric acid into nitrobarbituric acid (Baeuer, Ann., 130, 140); potassium permanganate oxidizes barbituric acid into hydriodic acid (Biltz, Heyn, Ber., 52, 1302). Biltz and Heyn (Ann., 1917, 413, 60) prepared alloxan by the oxidation of uric acid by means of chlorine. Fischer and Helfferich ("Anleitung zur Darstellung organischer Präparate," 10th ed., page 66, Braunschweig, 1922) used potassium chlorate and hydrochloric acid for the same reaction. Alloxantin, xanthin, uramil and thiouramil likewise can be oxidized to alloxan (Wöhler, Liebig, Ann., 1838, 26, 256; Fischer, Ann., 1882, 215, 310; Fischer, Ach, Ann., 1895, 288, 160); it is obvious that the starting materials used in these procedures are too difficultly available to render any one of them suitable for a large scale production.

In the past, several methods have been used for the technical preparation of alloxan. The oldest method is that of oxidizing uric acid which, however, has no practical importance today, since uric acid is much too expensive for technical purposes. A subsequently developed method is based on the oxidation of uramil, already mentioned. This procedure starts with barbituric acid, which is converted into nitrosobarbituric acid and reduced to uramil, which is then oxidized. The method requires four steps. It was abandoned when Bilmann and Berg (Ber., 1930, 63, 2201) devised a new method of preparing alloxan from barbituric acid, involving only two steps, namely,

2

the formation of benzalbarbituric acid and its oxidation with chromic acid. Up to date, this is the simplest and cheapest manufacturing process for alloxan. However, Bilmann and Berg fail to recognize the possibility of direct oxidation of barbituric acid.

I have now discovered that barbituric acid itself can directly be oxidized to alloxan by reacting it with an oxidizing agent in a liquid reaction medium. The synthesis of alloxan from barbituric acid is thus reduced to one single step. I have found that this method is highly advantageous in contrast to the Bilmann-Berg procedure, because one essential step of that procedure is entirely omitted, since the conversion of the barbituric acid into its benzal derivative prior to oxidation is no longer required. The cost of the expensive benzaldehyde is thereby saved. The use of suitable oxidizing agents, such as chromic acid, chloric acid and manganese dioxide, is illustrated in the attached examples.

The direct chromic acid oxidation of barbituric acid has proven particularly useful in contrast to the same oxidation of benzalbarbituric acid. It requires only two-thirds of the amount of chromic acid consumed in the oxidation of benzalbarbituric acid; this holds true of all direct oxidation processes of barbituric acid since no oxidation agent is needed to oxidize a side chain, as, for instance, in benzalbarbituric acid. Furthermore, the mother liquors remaining after separation of the alloxan contain only negligible amounts of by-products besides chromium acetate, whereas the mother liquors obtained according to the procedure of Bilmann and Berg hold the total amount of benzoic acid originating from the benzal group of the benzalbarbituric acid. Since this benzoic acid is present as a complex chromium salt, the regeneration of the chromium presents difficulties which are avoided in the new procedure.

Chloric acid has the advantage that it is a comparatively cheap and yet powerful oxidant. Oxidation with chloric acid is preferentially carried out in the presence of a low proportion of vanadium pentoxide, as shown hereinafter in Example 2. The vanadium pentoxide functions as a catalyst in the reaction. It can be employed in aqueous solution. A solution of alloxan is thus obtained which can be used as such for further reactions. If it is desired to isolate the alloxan from the solution, it is possible to reduce the alloxan to a less soluble derivative such as alloxantin, which can easily be isolated and converted into alloxan by a simple procedure.

The following examples illustrate my invention:

Example 1

128 parts of barbituric acid containing 2 moles of water of crystallization are slowly added to a solution of 140 parts of chromium trioxide, also referred to in the art as chromic acid, in a mixture of 800 parts of glacial acetic acid and 80 parts of water. The mixture is stirred vigorously. The addition of the barbituric acid is made in such a way that the temperature of the reaction mixture does not exceed 55° C. After complete addition the mixture is stirred for one more hour at 55° to 60° C. Alloxan starts slowly to separate. The mixture is cooled to +5° and filtered. 104 g. of alloxan are directly obtained (81% of theoretical yield).

Example 2

384 parts of barbituric acid, 220 parts of sodium chlorate and 1 part of vanadium pentoxide are stirred at room temperature with 2500 parts of water. A solution of 115 parts of sulfuric acid (95%) in 1000 parts of water is slowly added over a period of several hours. The temperature rises slowly. The addition of the sulfuric acid is regulated in such a way that the temperature does not exceed 45° to 50°. The barbituric acid goes slowly into solution and a precipitate separates slowly. This precipitate is filtered off, the filtrate is chilled to 0° and a solution of 500 parts of stannous chloride in 500 parts of concentrated hydrochloric acid is added with stirring at such a rate that the temperature does not rise above +3°. Alloxanthin starts to precipitate after a short while. When all the stannous chloride solution is added, the alloxanthin is filtered immediately, washed with ice cold dilute hydrochloric acid and ice cold water. By recrystallization from boiling water pure alloxanthin is obtained. The yield amounts to about 350 parts (73% of the theoretical).

Example 3

Fifty-two parts of manganese dioxide, 500 parts of water, and 80 parts of sulfuric acid 95% are stirred at room temperature. 38.4 parts of barbituric acid are added in about 10 portions over a period of several hours. The well-stirred mixture warms up slightly. The temperature rises to about 40°, then drops slowly. When it has reached room temperature, the undissolved material is filtered off. The mother liquor is reduced with a solution of stannous chloride in hydrochloric acid at 0°. Alloxanthin separates and can be isolated by filtration.

What I claim is:

1. The process of preparing alloxan which comprises mixing and reacting barbituric acid with an oxidizing agent selected from the group consisting of chromic acid, chloric acid and manganese dioxide in an acid medium so as to produce alloxan.
2. The process of claim 1 in which chromic acid is used as the oxidizing agent.
3. The process of claim 1 in which chloric acid is used as the oxidizing agent.
4. The process of claim 1 in which the oxidizing agent employed is manganese dioxide.
5. The process which comprises mixing and reacting barbituric acid with chromium trioxide in acetic acid so as to produce alloxan.
- 10 6. The process of claim 5 in which the temperature is maintained below about 60° C.
7. The process which comprises mixing and reacting barbituric acid by adding an aqueous solution of sodium chlorate to a mixture of barbituric acid and dilute sulfuric acid containing a small amount of vanadium pentoxide so as to produce alloxan.
- 20 8. The process of claim 7 in which the temperature is maintained below about 60° C.
9. The process which comprises mixing and reacting barbituric acid with manganese dioxide in the presence of dilute sulfuric acid in an aqueous medium so as to produce alloxan.
- 30 10. The process which comprises mixing and reacting barbituric acid in an aqueous solution with an oxidizing agent selected from the group consisting of chromic acid, chloric acid and manganese dioxide so as to produce alloxan, reducing the alloxan to alloxanthin in the same solution without the separation of the alloxan from the solution in which it is formed, and separating the alloxanthin as a crystalline material from the aqueous solution.
- 35 11. The process of claim 10 in which the reduction is carried out by means of stannous chloride and hydrochloric acid.
